PROCESS OF MAKING PLASTER BOARD

Original Filed Dec. 12, 1921 2 Sheets-Sheet 2

Inventor
Morgan K. Armstrong
by Clarence C. Webeltop Atty.

UNITED STATES PATENT OFFICE.

MORGAN K. ARMSTRONG, OF HAMPTON, VIRGINIA.

PROCESS OF MAKING PLASTER BOARD.

Application filed December 12, 1921, Serial No. 521,577. Renewed July 29, 1925.

To all whom it may concern:

Be it known that I, MORGAN K. ARMSTRONG, a citizen of the United States, and a resident of Hampton, in the county of Elizabeth City and State of Virginia, have invented certain new and useful Improvements in Processes of Making Plaster Board; and I do hereby declare that the following is a full, clear, and exact description thereof, reference being had to the accompanying drawings, and to the letters of reference marked thereon, which form a part of this specification.

This invention relates to an improved process for making plaster board, and consists of the matters hereinafter described and more particularly pointed out in the appended claims.

The object of the invention is to provide a novel and improved process for the manufacture of plaster board of the kind described in an application executed of even date herewith, and comprising a plaster body and top and bottom covering sheets of paper or other fibrous material, with strips or bands of a nailing mixture forming the body at the edges of the board and finishing the edges thereof. In order to illustrate my process, I accompany the application with drawings showing a machine or apparatus by means of which my improved process may be carried out.

In the drawings:—

Figure 1 is a diagrammatic view of a longitudinal section through the apparatus. Figure 2 is a view representing a top plan view of Fig. 1.

Figure 3 is a view representing on an enlarged scale a transverse section through Figure 2 in a plane indicated by the line 3—3 of Figure 2.

Figure 4 is a view representing a horizontal section through Figure 3 in a plane indicated by the line 4—4 of Figure 3.

Figure 5 is a view representing on an enlarged scale a section through Figure 1 in the plane indicated by the line 5—5 of Fig. 1.

Figure 6 is a view representing a transverse section through the finished board.

My improved process is a continuous process and as to its general features is like the well-known continuous process by means of which plaster board, comprising top and bottom covering sheets and an interposed

body of plaster to which said sheets are adhered, has for a long time been made.

Referring to the drawings:—

The bottom covering sheet 10 is fed from a roll of paper 11 over a platform 12, towards a pair of vertically spaced rollers 13, 14. Before the paper reaches said rollers, a mixture of plaster 15 is laid on and roughly spread over the advancing bottom sheet, and as it reaches the rollers 13, 14 a top sheet 16, fed from a roll 17 over and about tension rollers 18, and then about and under the top roller 13, is laid on and adhered to the layer of plaster. From the rollers 13, 14 the board thus made is fed over an endless conveyor belt 19, which is made of sufficient length to permit the setting of the plaster before the strip of board reaches the end of said conveyor. The board is then cut to the desired lengths and is put into kilns to dry.

In the present process, in addition to the layer of plaster material, there is laid on the advancing bottom sheet the bands or strips of a nailing mixture which is to form the edge of the board. This mixture may be of any suitable composition, possessing the requisite properties of a nailing mixture,—that is to say, a plastic mixture which, when dry, may be penetrated by a nail without disintegration or cracking. Such a mixture may be made from tar, sawdust or other fibrous material and clay, mixed while hot.

In carrying out the process, and preferably, I make a board of double the intended width, which may be sawed or cut through the middle to provide two lengths of like board. To this end, in manufacturing the board according to the process as carried out on the apparatus illustrated herein, I apply to the advancing bottom covering sheet 11, bands or strips of the plaster nailing mixture 20, 20 at the edges of the bottom sheet, and an intermediate band of double width 21 along the longitudinal middle line of the sheet. The strips or bands of the plastic nailing mixture are applied to the advancing bottom sheet in the positions illustrated in Figure 2 by any suitable means. As shown, I have provided hoppers 20^a, 20^a, and 21^a, to which the soft plastic nailing mixture is supplied. Said hoppers are connected with tubular expressing tubes 22, in which work screws 23, adapted to express or drive the plastic nailing mixture out through a dis-

charge spout 24, which is formed to lay on the advancing bottom sheet the plastic nailing mixture in the form of flat ribbons of the desired thickness and width. The 5 screws for expressing the plastic nailing mixture are driven in any suitable manner (not shown). By this means and in this way the three bands of nailing mixture are laid on the advancing sheet, the surface of the 10 sheet between said bands being left free and exposed.

The plaster to form the main body of the board, instead of being applied to the whole width of the bottom sheet 11, as heretofore, 15 is applied to the intermediate widths or spaces 25, 26 (see Fig. 2), being directed thereon from suitable hoppers, not shown, by means of belts 25^a, 26^a, located at either side of the machine. The plaster is spread 20 over the sheet in the spaces 25, 26, intermediate the bands, to form the main body parts 25^b, 26^b of the board and when the top sheet is applied by the pressure of the roller 13 in the usual manner, said top sheet 25 is adhered not only to the main plaster body 25^b, 26^b but also to the nailing mixture bands 20, 21, 20. As the body with its covering 30 sheets passes between the rollers 13, 14, the plaster bodies 25^b, 26^b are forced into intimate contact at their edges with the proximate edges of the several bands 20, 21, 20, of nailing mixture so as to provide an intimate union and bond between the two different characters of material forming the 35 body of the board.

In order to hold the said nailing mix bands in position and to prevent the plaster mix of the main body from being forced over the top of said bands, I provide a plurality of mould plates 27, 27 and 28, 28, the 40 first two named being directed along the inner edge of the outer nailing mixture bands 20, 20, and the second two being located at either side of the central nailing 45 mixture band 21. These mould plates are preferably made of glass and are supported in any convenient manner, as for example, by the bars 29, 29 which extend transversely of the machine and are supported from the 50 platform 12 by means of straps 30 (see Fig. 3). The mould plates are mounted in brackets 31, each of which is secured to its bar 29 by means of a set-screw,—said bracket being slidable on the bar so as to be capable 55 of lateral adjustment thereon to adjust its position in accordance with the width of nailing mixture band that is to be applied. The front ends of said plates are curved as indicated at 32, to fit the bottom surface of 60 the top roller 13, and have ends or points 33 that terminate short of the vertical plane through the axes of the rollers 13, 14. The mould plates are attached to the brackets 31, as indicated, in such manner that they may 65 be adjusted longitudinally so as to bring the

points 33 nearer to or move them further from the said vertical plane through the axes of the rollers.

As the bottom sheet advances and as the 70 plaster mixture to form the body is applied, the mould plates prevent the plaster from coming into contact with the nailing mixture bands, said plates, as will be understood, being adjusted to bear lightly on the top surface of the advancing bottom sheet. As the 75 points 33 of said mould plates terminate short of the vertical plane through the axes of the rollers 13, 14,—that is to say, short of the narrowest space separating the surfaces of said rollers,—just before the body is reduced to the final intended thickness by passing between the rollers,—the plaster of the body parts 25^b, 26^b is forced laterally outward beyond said points against the proximate edges of the nailing mix bands 85 20, 21, 20, thus bringing about a forcing together of the several kinds of plastic material composing the body into intimate engagement at the point when the greatest pressure is exerted, with the result that a 90 bond is afterwards formed between them when the plaster sets.

In order to smooth up and make true the outer edges of the two outermost nailing mixture bands 20, 20, it is preferable to provide a scraper or shoe 34, which is supported in such manner as to engage the edges of the advancing board as the board passes through the vertical plane of the diameters of the rollers 13, 14. Said shoes as shown, are attached to the straps which support the forward bar 29.

In order to provide a bevel at the edges of the board, one of the rollers (as shown the top roller) is provided with a coniform enlargement 13^a, and in the case where the board is made of double width, as illustrated herein, the same roll is provided with a coniform enlargement 13^b at the middle,—the cones being oppositely disposed as shown in Figure 5.

After it is formed as above described, the board is carried over the endless conveyor 19, in the usual manner and allowed to dry or set, after which it is severed transversely 115 into the desired lengths, and longitudinally into the designed two widths of board, such as shown in Figure 6. The board is then dried in suitable kilns in a familiar manner. This completes the process.

The resulting board has true, straight edges which may be freely handled and nailed in position without danger of marring or breaking the board at or near said edges.

I claim as my invention:

1. The continuous process of making plaster board, which consists of advancing a bottom covering sheet of fibrous material of the width of the board to be made; of su- 130

- perimposing upon said sheet along its edges 5
ribbons of a plastic nailing mixture, said
ribbons being substantially rectangular in
cross-section and of predetermined width
and thickness; of spreading a plastic gypsum
mixture over said sheet intermediate
said ribbons; of confining said gypsum mixture
to prevent its overflow on said ribbons
while it is being spread; of superimposing a
top covering sheet of fibrous material of the
same width as that of the bottom sheet on
said several plastic mixtures; and of applying
pressure to the full width of said top sheet
to firmly adhere it to the top surface
of the said several mixtures comprising the
body of the board, at the same time forcing
the intermediate plastic mixture laterally
outward at its edges into intimate contact
with the proximate edges of said ribbons.
- 10 2. The continuous process of making plaster board, which consists of advancing a bottom covering sheet of fibrous material of double the width of the board to be made; of superimposing upon said sheet along its
edges and along its median line ribbons of
a plastic nailing mixture, said ribbons being
substantially rectangular in cross-section
and of predetermined width and thickness
and the ribbon along the median line being
double the width of the ribbons along the
edges; of spreading a plastic gypsum mixture
over said sheet intermediate said ribbons;
of confining said gypsum mixture to prevent
its overflow on said ribbons while it
is being spread; of superimposing a top cov-
ering sheet of fibrous material of the same
width as the width of said bottom sheet on
said plastic mixtures; and of applying pres-
sure to the full width of said top sheet to
firmly adhere it to the top surface of said
several plastic mixtures comprising the body
of the board, and at the same time forcing
the plastic mixture intermediate said rib-
bons laterally outward at its edges into in-
timate contact with the edges of said rib-
bons.
- 15 3. The continuous process of making plaster board, which consists of advancing a bottom covering sheet of fibrous material of
the width of the board to be made; of superimposing upon said sheet along its edges
ribbons of a plastic nailing mixture, said
ribbons being substantially rectangular in
cross-section and of predetermined width
and thickness; of spreading a plastic gypsum
mixture over said sheet intermediate said
ribbons; of confining said gypsum mixture
to prevent its overflow on said ribbons
while it is being spread; of superimposing a
top covering sheet of fibrous material of the
same width as that of the bottom sheet on
said several plastic mixtures; of applying
pressure to the full width of said top sheet
to firmly adhere it to the top surface of the
said several mixtures comprising the body
- 20 of the board, at the same time forcing the
intermediate plastic mixture laterally out-
ward at its edges into intimate contact with
the proximate edges of said ribbons; and of
facing the outer edges of said ribbons to
form and smooth the edges of the board.
- 25 4. The continuous process of making plaster board, which consists of advancing a bottom covering sheet of fibrous material of
the width of the board to be made; of superimposing upon said sheet in predetermined
lines ribbons of a plastic mixture capable of
being given a definite form in cross-section
when in a plastic state; of spreading a plas-
tic mixture of a different consistency over
said sheet intermediate said ribbons; of con-
fining said intermediate mixture to prevent
its overflow on said ribbons; of superimpos-
ing a top covering sheet of fibrous material
of the same width as said bottom sheet on
said several plastic mixtures; and of applying
pressure to the full width of said top sheet
to firmly adhere it to the top surface of
said several plastic mixtures comprising
the body of the board, and at the same time
forcing the intermediate plastic mixture lat-
erally outward at its edges into intimate
contact with the proximate edges of said
ribbons to join said several plastic mixtures
into a single body for the board.
- 30 5. The continuous process of making plaster board, which consists of advancing a bottom covering sheet of fibrous material of the
width of the board to be made; of superimposing upon said sheet along its edges rib-
bons of a plastic nailing mixture, said rib-
bons being substantially rectangular in
cross-section and of predetermined width
and thickness; of spreading a plastic gypsum
mixture over said sheet intermediate said
ribbons; of superimposing a top cov-
ering sheet of fibrous material of the same
width as that of the bottom sheet on said
several plastic mixtures; and of applying
pressure to the full width of said top
sheet to firmly adhere it to the top surface
of the said several mixtures comprising the
body of the board, at the same time forcing
the intermediate plastic mixture laterally
outward at its edges into intimate contact
with the proximate edges of said ribbons.
- 35 6. The continuous process of making plaster board, which consists of advancing a bottom covering sheet of fibrous material of
double the width of the board to be made; of superimposing upon said sheet along its
edges and along its median line ribbons of
a plastic nailing mixture, said ribbons being
substantially rectangular in cross-section
and of predetermined width and thickness
and the ribbon along the median line being
double the width of the ribbons along the
edges; of spreading a plastic gypsum mixture
over said sheet intermediate said rib-
bons; of superimposing a top covering sheet

of fibrous material of the same width as the width of said bottom sheet on said plastic mixtures; and of applying pressure to the full width of said top sheet to firmly adhere it to the top surface of said several plastic mixtures comprising the body of the board, and at the same time forcing the plastic mixture intermediate said ribbons laterally outward at its edges into intimate contact with the edges of said ribbons.

7. The continuous process of making plaster board which consists of advancing a bottom covering sheet of fibrous material of the width of the board to be made; of superimposing upon said sheet along its edges ribbons of a plastic nailing mixture, said ribbons being substantially rectangular in cross-section and of predetermined width and thickness; of spreading a plastic gypsum mixture over said sheet intermediate said ribbons; of superimposing a top covering sheet of fibrous material of the same width as that of the bottom sheet on said several plastic mixtures; of applying pressure to the full width of said top sheet to firmly adhere it to the top surface of the said several mixtures comprising the body of the board, at the same time forcing the intermediate plastic mixture laterally outward at its edges into intimate contact with

the proximate edges of said ribbons; and of facing the outer edges of said ribbons to form and smooth the edges of the board.

8. The continuous process of making plaster board, which consists of advancing a bottom covering sheet of fibrous material of the width of the board to be made; of superimposing upon said sheet in predetermined lines ribbons of a plastic mixture capable of being given a definite form in cross-section 40 when in a plastic state; of spreading a plastic mixture of a different consistency over said sheet intermediate said ribbons; of superimposing a top covering sheet of fibrous material of the same width as said bottom 45 sheet on said several plastic mixtures; and of applying pressure to the full width of said top sheet to firmly adhere it to the top surface of said several plastic mixtures comprising the body of the board, and at the same time forcing the intermediate plastic mixture laterally outward at its edges into intimate contact with the proximate edges of said ribbons to join said several plastic mixtures into a single body for the board.

In testimony that I claim the foregoing as my invention, I affix my signature this 11th day of July, A. D. 1921.

MORGAN K. ARMSTRONG.
